United States Patent Office

Des. 219,854
Patented Feb. 2, 1971

219,845

FALSE EYELASH APPLICATOR

Pearl Howard, 441 S. Barrington Ave.,
Los Angeles, Calif. 90049

Continuation-in-part of design application Ser. No. 15,009,
Nov. 19, 1968. This application Mar. 6, 1970, Ser. No.
21,773

Term of patent 14 years

Int. Cl. D3—99

U.S. Cl. D86—10

FIG. 1 is a top plan view of a false eyelash applicator showing my new design;

FIG. 2 is a side elevational view thereof;

FIG. 3 is a side elevational view thereof in an open position;

FIG. 4 is an end elevational view from the left of FIG. 2;

FIG. 5 is an end elevational view from the right of FIG. 2.

This is a continuation-in-part of application Ser. No. D.15,009, filed Nov. 19, 1968, and now abandoned.

I claim:

The ornamental design for a false eyelash applicator, as shown and described.
